UNITED STATES PATENT OFFICE

142,747

DESIGN FOR A DOLL OR SIMILAR ARTICLE

Mary M. Stevens, Rye, N. Y., and Ethel M. Rice,
Lynn, Mass.

Application August 19, 1944, Serial No. 114,943

Term of patent 14 years

(Cl. D34—4)

To all whom it may concern:

Be it known that Mary M. Stevens, a citizen of the United States and resident of Rye, county of Westchester, State of New York, and Ethel M. Rice, a citizen of the United States and resident of Lynn, county of Essex, State of Massachusetts, have invented a new, original, and ornamental Design for a Doll or Similar Article, of which the following is a specification, reference being had to the accompanying drawing, forming part thereof, in which,

Fig. 1 is a perspective view of a doll embodying my new design; and

Fig. 2 is a side elevational view of the said doll.

I claim:

The ornamental design for a doll or similar article, substantially as shown.

MARY M. STEVENS.
ETHEL M. RICE.
